Frank G. Shuman,

UNITED STATES PATENT OFFICE.

FRANK G. SHUMAN, OF CHICAGO, ILLINOIS.

PRICING OUTFIT.

1,261,447.

Specification of Letters Patent. Patented Apr. 2, 1918.

Application filed February 14, 1917. Serial No. 148,658.

To all whom it may concern:

Be it known that I, FRANK G. SHUMAN, a citizen of the United States, residing at Chicago, in the county of Cook and State 5 of Illinois, have invented a new and useful Pricing Outfit, of which the following is a specification.

By way of explanation it may be stated that customers in a store are somewhat loth 10 to inquire as to the prices of merchandise, particularly in the case of articles which sell for a few cents. This reluctance is due to the fact that an inquiry as to price consumes time and, further, arises out of the fact that 15 purchasers frequently desire to avoid the appearance of parsimony. The present invention aims to provide a novel means whereby the prices of articles may be displayed prominently, and to provide a novel 20 means whereby the labels which indicate the different prices may be held on a shelf or like support.

The device herein disclosed aims to prevent, through a prominent display of the 25 prices or articles, undercharging, overcharging, knocking down, and other evils attendant upon the conduct of a business in which the prices of articles are not displayed prominently before the purchaser.

With the above and other objects in view 30 which will appear as the description proceeds, the invention resides in the combination and arrangement of parts and in the details of construction hereinafter described 35 and claimed, it being understood that changes in the precise embodiment of the invention herein disclosed can be made within the scope of what is claimed, without departing from the spirit of the invention.

40 In the accompanying drawings:—

Figure 1 shows a device constructed in accordance with the present invention, applied to the forward edge of a shelf;

Fig. 2 is a section taken on the line 2—2

45 of Fig. 1;

Fig. 3 is a rear elevation of the combined display element and shelf grip shown in place in Fig. 1; and

Figs. 4, 5, 6, 7 and 8 are plan views showing 50 different kinds of labels which may be used in connection with the display element and shelf grip.

In the accompanying drawings, the numeral 1 denotes a support, such as a shelf.

55 With the forward edge of the shelf 1 is detachably assembled a combined display ele-

ment and shelf grip, preferably but not necessarily made of metal, and including a front plate 2 having a rectangular top 3 and provided at its lower edge with an upwardly and rearwardly inclined gripping flange 4 terminating in a depending lip 5. The lip 5 constitutes a means for manipulating the gripping flange 4, which is resilient, and it will be understood, when Fig. 2 is inspected, that the forward edge of the shelf 1 may be bound between the top 3 and the gripping flange 4, the combined display element and shelf grip thus being held detachably on the shelf 1.

On the forward face of the front plate 2 may be placed labels indicating the price of the merchandise to be dispensed, these labels preferably being gummed, so that they can be moistened and attached to the front plate 75 2. In carrying out the invention there is provided any desired number of labels, of the kind designated by the reference numeral 6 in Fig. 4, and carrying a numeral. Any desired number of labels 7 may be provided, the labels 7 carrying the word "for" 80 and a marking indicating value, such, for instance, as the 10¢ indication shown in Fig. 5. The labels 6 and 7 may be placed on the front plate 2, as shown in Fig. 1, and then it will be evident to a purchaser that 85 three articles are sold for ten cents.

There may be provided a label such as indicated in Fig. 6, the same bearing a numeral and a cent sign. The label 6 shown in Fig. 90 4 may be pasted on the label 8 and the label 8 may be pasted on the front plate 2 thus to indicate, for instance, that the price of an article is thirty-four cents.

In Fig. 7 there is shown a label 9 having a 95 zero mark 10, a cent sign 11 and a blank 12 below the cent sign 11. In Fig. 8 there appears a label 14 marked "Doz." The label 14 may be pasted onto the label 9 in the blank space 12, and such a label as the label 100 6 may be pasted on the label 9 in advance of the zero mark 10, thus indicating, for instance, that certain articles are sold at the rate of thirty-four cents a dozen.

The labels above described are illustrative 105 of the many kinds of labels which can be used in connection with the combined display element and shelf grip shown in place in Figs. 1 and 2.

Having thus described the invention, what 110 is claimed is:—

A combined tag-carrier and shelf-grip

consisting solely of a rectangular strip having a common width from end to end, and including, in a one-piece four-edged structure, a flat front plate of sufficient width to 5 receive a label, a flat imperforate top connected with the upper edge of the front plate and disposed at right angles to the front plate, a flat imperforate gripping flange connected with the lower edge of the front 10 plate and extended upwardly at an acute

angle thereto, and a flat imperforate lip depending from the rear edge of the flange.

In testimony that I claim the foregoing as my own, I have hereto affixed my signature in the presence of two witnesses.

FRANK G. SHUMAN.
